UNITED STATES PATENT OFFICE.

JAMES CARPENTER, OF MORAVIA, NEW YORK.

BARBED FENCE.

SPECIFICATION forming part of Letters Patent No. 258,888, dated June 6, 1882.

Application filed October 7, 1881. (No model)

To all whom it may concern:

Be it known that I, JAMES CARPENTER, of Moravia, in the county of Cayuga, in the State of New York, have invented new and useful 5 Improvements in Barbed Fence-Wire, of which the following, taken in connection with the accompanying drawings, is a full, clear, and exact description.

This invention relates to a novel construction of fence-wire which is capable of adjusting itself to the expansion and contraction under the variations in the temperature of the weather, and thus preventing to a great extent the sagging of the wire incident to the expansion of the same, as well as the breaking of the wire or its fastenings on the posts by undue strain caused by contraction, said wire also possessing the advantages of filling a greater space in the fence and being more conspicuous 20 than ordinary fence-wire, and less liable to twist in unrolling it from the reel and securing it to the fence-posts, and is therefore far more convenient than the majority of fence-wires heretofore used.

25 The invention is fully illustrated in the annexed drawings, where Figure 1 is a side view, and Fig. 2 an end view, of the improved fence-wire and its attachment to the post.

Similar letters of reference indicate corresponding parts.

A represents the fence-wire, which I slightly compress or flatten into an elliptic or oval form in cross-section, as seen in Fig. 2. I bend said wire serpentine or into a series of 35 waves, B B, in the direction of its length and in plane parallel to the greater diameter of the wire, said bents allowing the wire to expand and contract, and thus adjust itself, and at the same time filling a greater space in the 40 fence and rendering the wire more conspicuous, as hereinbefore set forth. At the center of each of the successive bents I provide the wire A with a barb, C, which is integral therewith, and projects outward from said bents, 45 respectively, in opposite directions and in the same plane as the greater diameter of the wire. The said barbs I form of lateral dis-

tention of the body of the wire, which may be made either simultaneously with the manufacture of the wire or pressed out of the wire by 50 suitable dies.

By applying the barbs to the highest and lowest points of the successive waves of the serpentine wire the projection of the barbs is rendered more prominent, and therefore said 55 barbs may be made shorter than is usually required, and are consequently less liable to injure live stock coming in contact with them.

By attaching the described wire A to the fence-post P by a staple, D, or other suitable 60 fastening applied to the wire at the highest and lowest points of two reversed bents, B B, said wire is held with its greater diameter and with its bents in a vertical plane, thereby stiffening the same and preventing to a great extent the sagging thereof.

Having described my invention, what I claim as new, and desire to secure by Letters Patent, is—

1. A fence-wire of oval or elliptic form in 70 cross-section, and bent serpentine or waving longitudinally and in the same plane as the greater diameter of the said wire, as shown and set forth.

2. A fence-wire bent serpentine or waving 75 in the direction of its length, and having projecting from the alternate upward and downward bents or curves respectively upward and downward projecting barbs.

3. A fence-wire bent serpentine or waving in 80 the direction of its length, and secured with its bents in a vertical plane by fastenings to the post at the highest and lowest points of two or more of the bents in the wire, substantially as and for the purpose set forth. 85

In testimony whereof I have hereunto signed my name and affixed my seal, in the presence of two attesting witnesses, at Syracuse, in the county of Onondaga, in the State of New York, this 1st day of October, 1881.

JAMES CARPENTER. [L. S.]
